UNITED STATES PATENT OFFICE.

MILON J. DEMOREST, OF BELDING, MICHIGAN

CONCRETE-MIXER.

No. 922,860.

Specification of Letters Patent. Patented May 25, 1909.

Application filed January 31, 1908. Serial No. 413,689.

To all whom it may concern:

Be it known that I, MILON J. DEMOREST, a citizen of the United States of America, residing at Belding, in the county of Ionia and 5 State of Michigan, have invented certain new and useful Improvements in Concrete-Mixers; and I do hereby declare the following to be a full, clear, and exact description of the invention, such as will enable others 10 skilled in the art to which it appertains to make and use the same.

My invention relates to improvements in concrete mixers and its object is to provide a simple and effective device that will permit 15 the passage of stones or other obstructions without varying the proportions of the material, and to provide the device with various new and useful features hereinafter more fully described and particularly pointed out 20 in the claims.

Heretofore it has been usual to provide a yielding member to permit a stone to pass, which operated to at the same time permit an excess of sand or other material to pass 25 with the stone, thus resulting in an irregular proportion of the material. In my device herein described, any increase of feed of one ingredient due to the passage of a stone is accompanied by a like increase of the other 30 ingredient so that the proportions remain constant, and in case of passage of stones of moderate size the machine does not need to yield at all as will hereafter appear.

Referring to the accompanying drawings, 35 Figure 1. is a side elevation of a device embodying my invention; Fig. 2. an inclined horizontal section on the line 2—2 of Fig. 1; Fig. 3. a vertical section of the same on the line 3—3 of Fig. 2. Fig. 4. a detail in end elevation; Fig. 5. an enlarged detail in plan view; and, Fig. 6 an end elevation opposite to Fig. 4. with parts broken away.

Like numbers refer to like parts in all of the figures.

1 represents a horizontally disposed angle iron frame mounted on suitable wheels for supporting and moving the device from place to place. Upon this frame are various upwardly extended supports 2 supporting a receptacle 3 divided by a vertical partition 4 into two parts forming two hoppers to respectively contain the cement and sand. They also support a water tank 5 and shelf 6 on which latter may be placed the bags of cement.

7 represents the mixing drum which con-

sists essentially of a tube open at both ends, supported at the lower end upon rollers 25 and supported at the upper end by a spider or pulley 33 in the upper end of the drum, in 60 the axis of which drum is rigidly inserted a shaft 8 extending outward through the receptacle and journaled in a bearing 9 on the front of the same, said shaft having on its outer end a pulley 22 and a crank 23 for 65 manually operating the machine. Any convenient agitator may be attached to this shaft to act on the contents of the hoppers.

A thrust bearing 24 is inserted between the bearing 9 and pulley 22 to take the downward thrust due to the inclination of the shaft and drum. The upper part of the receptacle is preferably of sheet metal secured to a frame attached to the supports 2. This receptacle is tapered downward and terminates in a cast metal bottom portion 10 supporting the bearing 9. This bottom is formed with segmental openings at the lower end beneath the respective hoppers, and is provided with an elastic packing 11 secured 80 thereto and projecting below the same and at its lower edge engaging a rotary disk 12 arranged substantially horizontal beneath the bottom of the hoppers. The disk is preferably slightly conical to aid in discharging the 85 material therefrom. Walls 36 and 36^a to the hoppers extend upward from the disk and radially from near its axis, being secured to the side walls of the hoppers at their outer edges. The partition 4 and these walls thus 90 form substantially two segmental chambers at the bottom of the hopper, one for cement and the other for sand and closed at the bottom by the disk. A segmental portion of the disk is outside the hoppers and extends within the upper end of the drum 7. This portion is engaged by a scraper 37 mounted on pivoted arms 38 attached to the wall 36 whereby the scraper will rest upon the disk 95 by gravity and rise and fall therewith and thus scrape the material from the same and discharge it into the upper end of the drum. 100

Beneath the disk 12 is a grooved pulley 13 engaged by a round endless belt 20 extending over idlers 21 mounted on an arm extending 105 downward from the bearing 9 and engaged by the pulley 22 whereby the disk is rotated. The disk 12 and pulley 13 are mounted on a vertically disposed and slightly inclined shaft 14, and supported in yielding contact 110 with the packing on the bottom of the hoppers by means of a spring 18 surrounding the

shaft, engaging a thrust collar 17 on the shaft, and supported at the lower end by a bracket 19 on the frame 1. This shaft 14 is also provided with bearing rollers 15 mounted on a bracket 16 and the shaft held in contact therewith by the tension of the belt 20. The shaft is movable vertically whenever any solid obstruction passes under the gates sufficiently large and rigid to cause the spring to yield. The partition 36 extends down close to the disk and retains the cement in the hopper bottom. The partition 4 is spaced apart from the disk at the bottom and provided with a vertically adjustable gate 34 to regulate the quantity of cement passing under the partition. The wall 36^a is also spaced apart at a greater distance from the disk than the partition 4 whereby both the sand and cement pass thereunder and the quantity of sand passing is regulated by a vertically adjustable gate 35 (see Fig. 6). About two-thirds of the upper portion of the cylinder 7 is provided with buckets 32 to carry the dry material upward and spill the same into the bottom of the cylinder to thus thoroughly mix the said material before the addition of water thereto. To supply water, a pipe 27 extends downward from the tank 5 and the flow of water is controlled by a valve 26 therein. This pipe is provided with a union 28 forming a rotative joint and is supported in a bearing 31 attached to one of the supports 2. This pipe extends downward opposite the lower end of the drum and thence inward within the same to near the lower ends of the buckets 32 and close to one side of the drum and above its axis, being perforated at the inner end for the discharge of water. On this inner part of the pipe are mounted arms 40 extending downward and toward the inner surface of the drum, on which arms is fixed a scraper 41 yieldingly engaging the inner surface of the drum to remove the material adhering thereto. This scraper is yieldingly held in contact with the drum by means of an arm 29 fixed on the pipe 27 and having attached a spring 30, the tension of which spring rocks the pipe and yieldingly forces the scraper 41 in contact with the inner surface of the drum.

It will be noted that the cement is first laid on the surface of the disk and then the sand deposited above the cement. Thus any stones in the sand will be out of contact with the disk and in passing under the gate to get out of the hopper will be depressed into the cement and will not clog or break the machine. I, therefore, do not find the yielding support necessary except in case stones of considerable size are put into the sand hopper. So also the cement only comes between the disk and the lower edge of the hopper bottom and thus I avoid wear and friction due to sand in this joint.

What I claim is:

1. In a concrete mixer, a hopper open at the bottom, a disk partially beneath the hopper and closing the same, means for rotating the disk, a yielding support for the disk, a gate in the wall of the hopper above the disk, a vertically movable scraper engaging the disk outside the hopper and a mixing drum adapted to receive the material.
2. In a concrete mixer, the combination of a hopper having a vertical partition and a segmental opening at each side of the partition, an adjustable gate in the partition, a disk partially beneath the hopper and closing the openings therein, a gate in the wall of the hopper and above the disk, means for rotating the disk, a scraper attached to one wall of the hopper and engaging the disk outside of the hopper and a mixing drum adapted to receive the material.
3. In a concrete mixer, the combination of a hopper having a partition and two segmental bottom openings, radial walls to the hopper, an adjustable gate in the partition, an adjustable gate in one of the radial walls, pivoted arms attached to the other radial wall, a scraper attached to said arms, a rotative disk partially beneath the hopper and closing the openings thereof, and also engaged by the scraper, means for rotating the disk, a yielding support for the disk and a mixing drum adapted to receive the material.
4. In a concrete mixer, a hopper open at the bottom, a disk partially beneath the hopper and closing the same, a shaft on which the disk is mounted, a spring supporting the shaft and disk, means for rotating the same, a vertically movable scraper engaging the disk outside the hopper and a mixing drum adapted to receive the material.
5. In a concrete mixer, a rotative mixing drum, a shaft extending from the end of the drum, a crank and pulley on the outer end of the shaft, a hopper inclosing a middle portion of the shaft and having a segmental bottom opening, a disk partially beneath the hopper and closing said opening, a shaft on which the disk is mounted, a pulley on the shaft, and a belt connecting the said pulley and the pulley on the first named shaft.
6. In a concrete mixer, an inclined mixing drum, rollers supporting the lower end of the drum, a shaft supporting the upper end of the drum and projecting from the axis thereof, means for rotating the shaft and drum, a hopper inclosing the middle part of the shaft and having segmental bottom openings and a partition, a gate in the partition, a bearing for the shaft located on the side of the hopper, a disk partially beneath the hopper and closing the bottom openings.

thereof, a vertically disposed shaft on which the disk is mounted, a pulley beneath the disk, a belt connecting said pulley with the pulley on the first named shaft, idlers engaging the belt, rollers engaging one side of the shaft in opposition to the belt, a thrust collar on the shaft, a spring surrounding the shaft and engaging said collar, and a

lower bearing for the shaft supporting the spring. 10

In testimony whereof I affix my signature in presence of two witnesses.
